UNITED STATES PATENT OFFICE.

HENRY A. THAYER, OF NEW YORK, N. Y., ASSIGNOR, BY MESNE ASSIGNMENTS, TO GEORGE S. HULBERT, OF EAST ORANGE, NEW JERSEY.

FOLDING BED.

SPECIFICATION forming part of Letters Patent No. 337,635, dated March 9, 1886.

Application filed May 2, 1885. Serial No. 164,170. (No model.)

To all whom it may concern:

- Be it known that I, HENRY A. THAYER, a citizen of the United States, residing in New York city, New York, have made a certain 5 Improvement in Folding Beds, of which I declare the following to be a full, clear, and exact description, reference being had to the accompanying drawings, which form a part hereof.
- 10 The invention relates to a new and improved construction of the head-board, or a part thereof, of such folding bed, whereby the head-board, or a part thereof, when the bed is extended or unfolded, becomes the cover or shelf 15 when the bed is folded, and the outer or exposed side or face of the head-board becomes the under and protected side of the shelf or cover.

The accompanying drawings represent my 20 improvement. Figure 1 is a rear view of the head of a bed embodying it. Fig. 2 is a side view, partly in section, of the bed extended, and Fig. 3 of the bed closed up.

Like letters of reference indicate like parts. 25 A is the general frame work of the head of the bed, which is fixed or stationary.

B is the bed proper, or folding part of the bed. These parts A and B may be of any desired construction, and may be connected together 30 in any desired way, so that the part B can be rolled or folded up against the part A and held there when the bed is not required to be extended.

C is a panel forming the head-board when 35 the bed is unfolded, and adapted to form a cover or shelf over the part B when that part is rolled or folded up against the part A, and it is so mounted and connected with the part A that the face or surface of the panel which 40 forms the exposed face, as a head-board, becomes the under and protected face of the cover or shelf. This mode of combining the panel C with the fixed head part A of the bed enables me to employ one side or surface of 45 the panel as the effective, because the exposed side of the head-board, and to employ the other side or surface of the panel as the effective, because the upper side of the shelf.

Heretofore all folding beds which have employed a hinged or pivoted head-board as a cover during such times as the bed is folded

up have so combined such head-board with the fixed head-frame of the bed that the front and exposed side of the head-board became the upper and useful side or surface of the cover or shelf. This has made it impossible to employ the cover as an effective shelf, by reason of the injury to the ornamental work of the head-board resulting therefrom, or has necessitated the use of unornamented and plain wood head- 55 boards. Hinges and such other connections have been needed, that are unsightly when the bed is unfolded and the panel used as a head-board. 60

My improvement enables me to employ 65 panels that are highly ornamental, veneered, or carved on one side and plain and unornamented on the other side, whereby the panel, when in its operative position as a head-board, presents a highly-ornamental face, and when 70 in its operative position as a covering shelf presents a plain and effective shelf-surface, which may be freely used as a shelf without the slightest danger of injury to the head-board of the bed.

To accomplish the purpose of my improvement it is necessary to connect the lower edge of the panel C, when in position as a head-board, with the frame A by a sliding connection, whereby the panel may be raised from 80 that position into its operative position as a shelf, the upper edge of the head-board panel swinging outward and becoming the front edge of the shelf-panel.

The particular mode of connecting the panel 85 C with the fixed head part A which I prefer to use is shown in the drawings. The panel C is shown in Figs. 1 and 2 in its operative position as a head-board. In such position it is held in place by a catch or latch, *a*, of any 90 well-known construction, at its upper part catching into the frame A, and preferably, also, by pins *b b* at its lower part projecting from the ends of the panel and taking loosely into and adapted to move up and down freely in 95 ways or grooves *c c*, cut in the frame A at each side of the panel C. Attached to the lower part of this head-board panel, as it stands in Figs. 1 and 2, is a band or bands, *d d*, having a weight or weights, *e e*, at the other end and 100 passing over a pulley or pulleys, *f f*, placed, as shown in Figs. 1, 2, and 3, at or above the

position the panel C is to occupy when in position as a covering-shelf when the bed is folded.

When pins *b b* are used, the ways or grooves *c c* in which they slide must be long enough to enable the panel C to be moved from its position as a head-board (shown in Figs. 1 and 2) to its position as a covering-shelf, (shown in Fig. 3.) The weights *ee* assist in this raising of the panel.

The weights and bands may of course be varied in their details of construction, and may be omitted altogether if the panel C is made light; but I prefer to use them.

Fig. 3 shows the bed folded and the panel C in its position as a covering-shelf, in which the back surface of the panel as a head-board has become the upper and effective surface of the panel as a shelf.

What I claim as new, and desire to secure by Letters Patent, is—

1. In combination with the fixed head-frame A and folding part B of a folding bed, the movable panel C, constructed with pin-

and-groove sliding connection with frame A, 25 whereby to present one surface as a head-board and the other surface as a covering-shelf, substantially as and for the purposes set forth.

2. In combination with the fixed head-frame A and folding part B of a folding bed, the movable panel C, having attached counter-weights and constructed with pin-and-groove sliding connection with frame A, 30 whereby to present one surface as a head-board and the other surface as a covering-shelf, substantially as and for the purposes set forth.

3. In combination with the frame A, having grooves *c c*, and the bed proper, B, the 35 counterweighted panel C, having pins *b b*, all combined, substantially as and for the purposes set forth.

HENRY A. THAYER.
